[57] ABSTRACT

Corrugated spacers are disposed between winding layers of a transformer winding to enable circulation of air between the layers. Elongated reinforcing rods are placed in corrugations at the corner regions of the winding and adjacent wedges between the winding and the transformer core. Dielectric sheaths of relatively high dielectric constant are disposed between the outermost and innermost winding layers while relatively low dielectric constant sheaths are placed between adjacent pairs of interior layers, thereby to equalize the distributed capacitance between adjacent layers. A dielectric barrier between the high and low voltage windings of a transformer consists of a sheath of dielectric layers wherein the inner and outermost layers have a higher dielectric constant than the interior layers.

INSULATION STRUCTURE TRANSFORMER WINDINGS

RELATED APPLICATIONS

This application relates to copending application Ser. No. 237,639 filed Mar. 24, 1972 entitled "Transformer Winding Structure Using Corrugated Spacers" in the names of Weber and Ruckel and assigned to the assignee of the present invention, and which claims aspects of the mechanical structure and support of the transformer winding of the present invention.

BRIEF SUMMARY OF THE INVENTION

This invention relates to the novel arrangement of dielectric sheaths used in the insulation of transformer type windings in order to obtain a more linear distribution of impulse voltage between transformer winding layers, and to decrease the dielectric stress on the barrier between high and low voltage windings.

A conventional winding structure for use in an electromagnetic device such as a reactor or transformer consists of a plurality of concentric layers of windings having a generally equal spacing with identical dielectric sheaths disposed between adjacent layers. It has been found that the first and last of these layers have a distributed capacitance to their adjacent windings which is lower than the capacitance between adjacent interior windings. Consequently, when an impulse voltage appears across the full winding, and is distributed between layers of the winding in accordance with their capacitive impedance, a higher voltage stress will appear on the first and last layers, than between interior layers. Thus the danger of a dielectric breakdown at the first and last layers of the winding under impulse voltage stress is increased.

In accordance with a first aspect of this invention, the dielectric sheath which insulates the first and last winding layers from their adjacent layers has a higher dielectric constant than the dielectric sheaths between adjacent interior layers. Therefore, the distributed capacitance of the first and last layers is increased, as compared to the distributed capacitance of the interior layers, so that a relatively smaller percentage of the full impulse voltage will appear across the first and last layers and impulse voltage distribution between layers will be more equal than where the same dielectric sheath material is used between all winding layers.

In accordance with a second aspect of the invention, the dielectric barrier sheath between high and low voltage windings is made of a composite of layers of low dielectric constant material sandwiched between outer, relatively high dielectric constant material. Thus, such barriers are conventionally formed of a common dielectric material of relatively low dielectric constant. In accordance with this aspect of the invention, however, the dielectric field lines will be spread apart and thus, the dielectric field gradient will be reduced. This then allows a reduction in the space between the high and low voltage windings, thereby saving material costs.

BRIEF DESCRIPTION OF THE DRAWINGS

FIG. 1 schematically illustrates a three-phase transformer which has three windings, which could be constructed in accordance with the present invention.

FIG. 2 schematically illustrates one high voltage winding of the transformer of FIG. 1.

FIG. 3a is an end elevational view of one end of a transformer such as the one of FIG. 1 which incorporates a coil having a construction which uses the present invention.

FIG. 3b is a partial side elevational view of FIG. 3a.

FIG. 4 is a cross-sectional view of FIG. 3a and is taken across section line 4-4 in FIG. 3a.

FIG. 5 is an enlarged view of a portion of FIG. 4 to illustrate the construction of the corrugation spacer.

FIG. 6 is an enlarged view, in perspective, of a portion of the high-voltage to low-voltage barrier shown in FIG. 4.

FIG. 7 is an enlarged view of a winding corner of FIG. 4 to illustrate the placement of rods and wedges in the winding support structure.

FIG. 8 schematically represents the distributed capacitances affecting the distribution of impulse voltage across the coil layers of a high voltage winding.

DETAILED DESCRIPTION OF THE DRAWINGS

FIG. 1 partly schematically illustrates a conventional transformer which may use the present invention in its winding structure. The transformer of FIG. 1 includes a magnetic core having three core legs 10, 11 and 12 joined by upper yoke 13 and lower yoke 14. The core may be made of conventional stacked laminations, and legs 10, 11 and 12 can be of any desired cross-section, which conventionally is generally rectangular. Each of core legs 10, 11 and 12 carry respective low voltage windings 20, 21 and 22 which are wound concentrically with outer high voltage windings 23, 24 and 25. The high and low voltage windings 20 to 25 may be arranged in any desired multiphase connection. The invention herein involves the specific construction of a winding which may be used in the transformer of FIG. 1, when the winding may be air cooled. It is to be noted, however, that the invention herein may be used for any type electrical winding, which is used in any type electromagnetic device.

While any terminal construction could be used for the various windings, each winding is shown in FIG. 1 as having a simple pair of terminals. FIG. 2 schematically shows that winding 25, for example, may have a plurality of tap terminals 30 to 34, and a second terminal 35. FIG. 2 further schematically illustrates the winding 25 as constructed of a plurality of identical layers of windings 36 to 43, and an end layer 44 which contains the taps 30 to 34. The schematically shown wound layers 36 to 43 are wound over an insulation barrier 45 to be later described, and which insulate the high voltage and low voltage windings. Taps 30 to 34 may be made in any desired manner. By way of example, one suitable tap arrangement is shown in copending application, Ser. No. 167,174, filed July 29, 1971, in the name of Ruckel et al.

FIG. 3a is an end view of the transformer of FIG. 1 when adapted with a winding construction made in accordance with the present invention, while FIG. 3b is a side-elevational view of FIG. 3a and specifically shows one winding and the taps 30 to 34 of the winding (winding 25 of FIG. 1). The winding construction as seen in FIGS. 3a and 3b shows the external high voltage winding 25, and protruding above and below the high volt-

age winding 25 is the high voltage to low voltage barrier 36a. A low voltage winding, not shown in FIGS. 3a and 3b, is contained within the barrier 36a and is wound concentrically with winding 25 on the core leg 12 of the transformer. The winding structure of the invention is most clearly shown in cross-section in FIG. 4.

FIG. 4 illustrates the square configuration of core leg 12 where it will be understood that core leg 12 could also have other configurations, if desired. The core leg 12 has wrapped thereon a glass tape layer 50 to insure insulation integrity between the grounded core and the winding to be connected thereon. The full winding is wound on a winding machine separately from the core and, in the embodiment herein, consists of a low voltage winding contained within the interior of the overall winding structure and an outer high voltage winding. The low voltage winding shown in FIG. 4 has an interior, upwardly extending terminal 51 which extends beyond the upper end of the winding, and may consist of a conductive foil 52 wound around an axis to form nine turns, which terminate in terminal 53. Note that terminals 52 and 53 correspond to the pair of terminals shown for the low voltage winding 22 in FIG. 1. The height of the low voltage winding is generally shown in dotted lines in FIG. 3a, with the low voltage winding 22 being contained within the insulation barrier 36a. A suitable insulation layer will be used over the surface of the material used for the low voltage winding. By way of example, a layer of asbestos reinforced with glass may be used to insulate the low voltage winding.

The insulation barrier 36a is then wound around the exterior of the low voltage winding 22 where the insulation barrier 36a consists of a composite of high dielectric and low dielectric layers, most clearly shown in FIG. 6. Thus, in FIG. 6, the barrier 36a consists of two outer layers 60 and 61 of a relatively high dielectric constant material with, for example, 14 interior layers 62 of a relatively low dielectric constant material. Good results have been obtained when using mica having a thickness of about 0.010 inch for the outer layers 60 and 61, and using a lower dielectric constant material, such as a material known as Nomex M, having a thickness of 0.010 inch for each of the 14 interior layers 62. Nomex M is a trademark of DuPont, and generally is a composite of nylon and mica.

By using materials of a relatively high dielectric constant in the area of high dielectric stress between the high and low voltage windings, the dielectric field lines distributed between layers 60 and 61 of FIG. 6 will be relatively spread apart thereby to decrease the dielectric gradient. Thus, it is possible to reduce the space between the high and low voltage windings, thereby saving material costs.

The high voltage winding 25 is then wound on top of the barrier 36a and consists of the nine layers 36 to 44, wherein the layers 36 and 42 may each contain 53 turns of aluminum wire which can, for example, have a cross-section of 0.115 by 0.375, which wire is appropriately insulated. Layer 43 may then have 49 turns, while the outer layer 44, which contains the taps 30 to 34, may have 48 turns. It will be noted that a start terminal (terminal 35 in FIG. 1) will come from the first layer 36, while the second terminal of the high voltage winding 25 in FIG. 1 could, for example, be the tap terminal 34 of FIG. 2.

In order to provide appropriate air cooling, whether forced air cooling, or natural convection cooling, each of the winding layers of both the high voltage and low voltage windings are spaced by insulation corrugated spacers. By way of example, corrugated spacers 70 and 71 are typically shown, respectively, between the first and second, and second and third windings of the low voltage winding 22. These corrugated spacers are shown in more detail in FIG. 5, where it is seen that they have an undulating configuration which defines side-by-side air channels which extend along the full length of the winding layers. Preferably, the corrugations will have a total thickness or excursion of at least three-eighths inch in order to define sufficiently large area air channels to allow a copious flow of cooling air through the channels.

In addition, these corrugations are made of a material which is capable of withstanding the relatively high temperature rise of a dry-type or air-cooled transformer. Good results have been obtained with corrugations made of polyimid resins, such as Gemon-L, made by the General Electric Corporation. Other suitable materials are moldable materials, such as Glastic 200, made by the Glastic Corporation, or HST, made by the Haysite Corporation. The material thickness of these corrugations may be about one thirty-second inch to provide satisfactory mechanical strength over most of the area of the corrugations. It will be noted that these corrugations could be crushed at high stress levels of the winding, but this problem is solved through the use of novel reinforcing rods to be described hereinafter.

Corrugations similar to corrugations 70 and 71 are disposed between each of the winding layers of the low voltage winding, although if desired, corrugations between only selected pairs of layers could be used. In the preferred embodiment of the invention, however, and as shown in FIGS. 4 and 5, corrugation spacers are provided between each of the foil winding layers 72, 73 and 74, as well as the remaining foil layers. It should be specifically noted that the corrugation region is made on selected peripheral portions of the coil which are disposed externally of the planes defined by the sides of yokes 13 and 14. In this manner, a clear air passage from the bottom of the transformer to the top is defined without interference from the yokes of the transformer.

A similar arrangement of corrugation spacers of identical material to spacers 70 and 71 is provided for the high voltage winding. Thus, corrugation spacers such as spacers 75 and 76 are disposed between winding layers 36 and 37, and 37 and 38, respectively. Similar corrugation structures are provided between each of the other winding layers of the high voltage winding. It will be seen that the corrugation spacer used for the high voltage winding also define air channels on the outside of the yokes of the transformer, thereby to provide clear unrestricted air-flow channels through which cooling air may be carried.

In addition, and in the winding shown in FIG. 4, corrugation spacers 77 and 78 are formed in the region passing between the yokes 13 and 14 of the transformer, and between winding layers 38 and 39 to help conduct heat from this interior portion of the winding even though the cooling air path will be partly blocked by the yokes 13 and 14.

As pointed out previously, the corrugation structure is sufficiently strong to maintain its configuration and physical strength in most parts of the coil. However, in high stress regions, it is possible that the corrugation could be crushed. In order to prevent the local crushing of the corrugation, and as shown in FIG. 4, the corner regions at which the winding layers bend are reinforced by insulation rods disposed within the corrugation and adjacent the corner region. Typical insulation rods are shown as rods 80, 81, 82, 83 and 84, which are generally disposed at the last corrugation region of their respective corrugation spacers, and at the region where the winding layer turns a corner. The insulation rods will then support and prevent the corrugation from collapsing during winding and extend the full length of the corrugation and may be secured thereto as by gluing.

The outer diameter of these rods will be approximately equal to the excursion of the corrugation. Thus, in FIG. 7, rods 85 and 86 may have a diameter of approximately five-sixteenths inch where the corrugations might have a total excursion, or total thickness, from peak to peak of three-eighths inch, and a wall thickness of one thirty-second inch.

In order to assemble the completely wound winding on the core 12, the upper yoke member 13 is disassembled in standard fashion, and the total winding is mounted concentrically with the winding leg 12, and is secured in place on the winding leg 12 by appropriate mounting structures, which could include insulation wedge members, such as the wedge members 90 to 95 shown in FIG. 4. These insulation wedges are simply elongated sticks which may be slightly wedge-shaped and which are forced between the interior of the winding and the exterior of the core leg 12. It has been found useful to dispose reinforcing rods in the first corrugation 70 at regions adjacent these wedge members to prevent local collapse of the interior corrugation 70.

Thus, in FIG. 4 it is seen that insulation rods, for example, rods 96 and 97 are placed adjacent the wedges 91 and 92 to prevent local collapse of the corrugation 70 at these regions.

A further important feature of the winding structure of FIG. 4 consists of the use of selective dielectric layers between the winding layers forming the high voltage winding. Thus, as shown in FIG. 4, a dielectric sheath or layer of tape is formed between each of the winding layers. These dielectric sheaths consist, for example, of the sheaths 101 to 109.

In accordance with an important feature of the present invention, the inner and outermost sheaths 101 and 109 of the high voltage winding are made of a material having a dielectric constant which is higher than the dielectric constant of the interior dielectric sheaths 102 to 108. Thus, each of the winding layers 36 to 44 may be equally spaced, for example, by three-eighths inch, but the insulation sheaths 102 to 108 are formed of two layers of 0.01 inch thick Nomex M, while the exterior insulation layers 101 and 109 are formed of, for example, two layers of 0.010 inch thick mica. With this structure, materials of higher dielectric constant are disposed between the first and last layers of the high voltage winding, thereby to increase the distributed capacitance of the first and last layers of the transformer winding in order to substantially equalize

the capacitance between all layers in order to cause equal voltage distribution of an impulse voltage applied to the high voltage winding.

This construction can be better understood in connection with FIG. 8, which schematically illustrates the high voltage winding 25 in connection with its distributed capacitances. Thus, there is an imaginary neutral plane shown by the dotted lines N between each pair of adjacent winding layers, with the distributed capacitance between winding layers being schematically illustrated as capacitances connected from the winding to the neutral plane. The total winding will be coupled to ground through the equivalent capacitances C_{o1} and C_{o2} . However, the equivalent layer capacitances of the first layer 36 to the second layer 37 and of the outer layer 44 to the next innermost layer 43 will be a capacitance C_L which is smaller than the distributed capacitances C_L between the remaining interior adjacent layers 37 to 43. Consequently, an impulse voltage applied to the high voltage winding could, for example, due to the effect of a lightning stroke, not distribute equally between the winding layers, but rather a larger percentage of the voltage will appear between layers 36 and 37, and 43 and 44, than between the adjacent layers.

In accordance with the present invention, and by using higher dielectric constant material between the first and last pairs of layers, the equivalent capacitance between these layers is increased to a value approaching that of the distributed capacitance between the remaining interior layers, thereby to improve the voltage distribution pattern across the winding due to impulse voltages. Note that this selection of different dielectric constant materials allows the transformer winding construction to use identical interlayer spacing thereby simplifying the manufacture of the transformer. Clearly, other combinations of dielectric materials could have been selected, if desired.

Although there has been described a preferred embodiment of this novel invention, many variations and modifications will now be apparent to those skilled in the art. Therefore, this invention is to be limited, not by the specific disclosure herein, but only by the appended claims.

The embodiments of the invention in which an exclusive privilege or property is claimed are defined as follows:

1. A winding for an electromagnetic device; said winding comprising a continuous conductor wound to form a plurality of turns around an axis; said winding consisting of a plurality of concentric layers; a plurality of layers of dielectric material, each disposed between adjacent pairs of concentric layers of said winding; first and second layers of said plurality of layers of dielectric material disposed between the outermost pair and innermost pair of winding layers having a higher dielectric constant than the remaining dielectric layers disposed between adjacent interior layers of said winding.

2. The winding of claim 1 wherein the distributed capacitance between each adjacent pair of winding layers is approximately equal.

3. The winding of claim 1 wherein each of said winding layers is substantially identical in construction and wherein each of said layers is spaced from adjacent

layers by an identical spacing; said first and second dielectric layers having a dielectric constant which is sufficiently high to increase the distributed capacitance of said exterior and interior pairs of winding layers to a value substantially equal to the distributed capacitance between the said interior winding layers which are insulated by relatively lower dielectric constant layers of dielectric material.

4. A transformer winding comprising, in combination:

a plurality of substantially identical concentric winding layers connected in circuit relation with one another;

a plurality of layers of dielectric material, said plurality of layers of dielectric material respectively disposed between respective adjacent pairs of said winding layers and being concentric and coextensive with said respective pairs of winding layers;

the outermost and innermost of said layers of dielectric material, disposed respectively between the outermost and innermost pairs of adjacent winding layers, and having a higher dielectric constant than the remaining layers of said plurality of layers, thereby to make the distributed capacitance between each pair of adjacent winding layers approximately equal.

5. The transformer winding of claim 4 wherein each of said adjacent pairs of winding layers has an approximately equal spacing.

6. An electrical transformer comprising, in combination:

a magnetic core structure;

a low voltage winding wound on said magnetic core structure;

a high voltage winding wound on said core structure and concentric with said low voltage winding;

said high voltage winding comprising a plurality of substantially identical concentric winding layers connected in circuit relation with one another;

a plurality of layers of dielectric material, said plurality of layers of dielectric material respectively disposed between respective adjacent pairs of said winding layers and being concentric and coexten-

sive with said respective pairs of winding layers; the outermost and innermost of said layers of dielectric material, disposed respectively between the outermost and innermost pairs of adjacent winding layers, and having a higher dielectric constant than the remaining layers of said plurality of layers, thereby to make the distributed capacitance between each pair of adjacent winding layers approximately equal.

10 7. The transformer winding of claim 6 wherein each of said adjacent pairs of winding layers has an approximately equal spacing.

15 8. The combination of claim 6 which further includes a dielectric barrier sleeve disposed concentrically with and between said high and low voltage windings; said dielectric barrier comprising a plurality of concentric layers of dielectric material which include outer layers of relatively high dielectric constant material and a plurality of inner layers of a relatively lower dielectric material.

20 9. An electrical transformer comprising, in combination:

25 a magnetic core structure;

a low voltage winding wound on said magnetic core structure;

a high voltage winding wound on said core structure and concentric with said low voltage winding;

said high voltage winding comprising a plurality of substantially identical concentric winding layers connected in circuit relation with one another;

30 a plurality of layers of dielectric material, said plurality of layers of dielectric material respectively disposed between respective adjacent pairs of said winding layers and being concentric and coextensive with said respective pairs of winding layers;

35 and a dielectric barrier sleeve disposed concentrically with and between said high and low voltage windings; said dielectric barrier comprising a plurality of concentric layers of dielectric material which include outer layers of relatively high dielectric constant material and a plurality of inner layers of a relatively lower dielectric constant material.
